UNITED STATES PATENT OFFICE.

WILLIAM H. MUZZY, OF CHICAGO, ILLINOIS.

GAS RESERVE FOR AUTOMOBILES.

Application filed January 22, 1921. Serial No. 439,203.

This invention relates to improvements in the reserve supply devices for fuel feeding systems for automobiles or the like and has more particular relation to improvements in such devices as suspend the operation of the engine when the main supply of the fuel is exhausted and permit the machine or engine to resume its operation upon the adjustment of certain devices which bring the reserve supply of fuel under the action of fuel feeding devices such for instance as the vacuum tank now in general use as a means of feeding fuel.

One of the objects of the invention is to provide improved devices for reserving a supply of fuel in a single undivided tank.

A further object of the invention is to provide devices for providing a reserve supply of fuel, which will not stick or leak gasoline line.

A still further object of the invention is to provide devices which are applicable to tanks already in use and may be fitted to tanks having different threaded connections by simply changing threaded sleeves having standard dimensions for receiving the reserve device.

The invention also has other objects all of which will be hereinafter more particularly set forth and claimed.

In the accompanying drawings forming part of this specification:

Figure 1 represents a vertical elevation, partly in section of the devices embodying my invention applied to a gasoline tank, the latter being broken away;

Figure 2 represents a top plan view of the same;

Figure 3 represents a detail side elevation of the lower end of the fuel feeding pipe;

Figure 4 represents a similar view of the lower end of the controlling sleeve;

Figure 5 represents a detail horizontal section on the line 5-5 of Figure 1;

Figure 6 represents a similar section on the line 6-6 of Figure 1, with the air vent open;

Figure 7 represents a similar horizontal section to Figure 6 with the air vent closed;

Figure 8 represents a detail vertical section through the attaching clamp for the flexible coil shown in Figure 9;

Figure 9 represents a vertical section and top plan view of the dash control attachment for the reserve device;

Figure 10 represents a vertical section

partly in elevation of a modified form of the device; and

Figure 11 represents a detail front elevation of the operating arm of the valve 60 sleeve.

The present invention is an improvement on the devices shown and described in my prior patents as follows: Patent 1,407,798—Feb. 28, 1922; Patent 1,407,799—Feb. 28, 1922; Patent No. 1,484,900, Feb. 26th, 1924.

Described in general terms the invention may be said to comprise a gasoline feed pipe extending down vertically into a gasoline tank and connected to a fuel feeding system such for instance as the well known vacuum feed system, or a pressure feed system. This feed pipe is unbroken and the control of the same is entirely from the exterior of the pipe and at a level approximately that of the reserve level of the gasoline in the tank. This permits of very loose fits and adjustments of the parts without in anywise disturbing the perfect operation of the parts. When the gasoline in the tank has reached the reserve level air will enter the pipe and thus destroy the suction and the feeding of the fuel will cease. Adjustment is now made of a sleeve loosely surrounding the feed pipe so that the reserve gasoline is drawn into the feed pipe and thus brought into use. This pipe and sleeve construction lends itself very readily to the application about the sleeve of different sized attaching nipples for different makes of cars. It is simply necessary to slip off one nipple and slip on the one for attachment to the car desired, the other parts all remaining the same. I have shown two forms for operating the parts one from the rear of the machine and the other from the instrument board of the machine.

In the aforesaid drawings 1 represents the gasoline tank at the rear of the machine, 2 the gasoline feed pipe preferably connected to a vacuum fuel feeding system, 3 the gasoline feed pipe which projects down into the gasoline in the tank 1, 4 the rotatable sleeve that loosely surrounds the pipe 3. This latter pipe is connected to an attaching nipple 20 to which the pipe 2 is connected by a compression coupling 21. The nipple 20 is formed with an index plate 19 on which the words "Off" and "Res" are formed. The operating handle 5 is rigidly connected to the upper end of the sleeve 4 so that when the handle is turned from the "Off" position

to the "Res" position the sleeve will be rotated and the elongated opening 3^a near the lower end of the pipe 3 will be closed by the opening 9 of the sleeve passing out of its registering position with said opening 3^a. In Figure 6 the openings are shown as registering while in Figure 7 they are shown as out of registering position. In this latter position the opening 3^a is of course closed and the pipe 3 practically remains unbroken for its entire length and will draw all of the gasoline out of the tank 1. The area of the openings 3^a and 9 are such that should these openings be slightly out of alignment because of the handle 5 being adjusted to a position not exactly on the line "Off" there still will be enough air pass into the pipe 3 to destroy the suction. In the reverse position the openings are well out of register and there is no chance of a misadjustment. The sleeve 4 is formed with a series of apertures 10 located preferably above the aperture 9. The office of these apertures is to admit gasoline freely to the slight space between the sleeve and the gasoline pipe 3 to seal this space against any chance of air pulling down between the sleeve and the pipe and through the opening 3^a. These apertures however are not essential to the operation of the device and may be omitted if desired.

As the gasoline feed pipe 3 extends down loosely through the sleeve 4 means must be provided for anchoring it in position to prevent it rising vertically and becoming displaced. To accomplish this result I provide the pipe 3 with a lateral pin 11 projecting through the same to one side of the middle line as shown in Figure 5. The sleeve 4 ends immediately above this pin and is formed with a projecting finger 12 which, when the handle 5 is operated, contacts with the opposite ends of the pin 11 and thus limits the rotary movements of the sleeve 4 and stops the sleeve in the proper position with the openings 3^a and 9 exactly registering. A collar 13 rests upon the ends of the pin 11. A coil spring 8 loosely surrounds the sleeve 4 and bears with one end against the collar 13 and with the opposite end against a washer 14 mounted loosely on the sleeve. The washer 14 bears against the under side of the attaching nipple 6 which is screw threaded as at 15 to be screwed into the plate 7 which is attached by rivets 22 to the top of the tank 1. The head of the nipple 6 is formed into a nut so that it may be turned down tight. A fibre washer 16 rests upon the top of the nipple 6 and is drawn down tight upon the same by the hub of the handle 5 which is fast to the sleeve 4. A washer 18 is located about the pipe 3 and between the disk 19 and the hub 17 of the handle. It will be seen from the above that the tension of the expanding spring

8 forces the pipe 3 downward and thus draws the disk 19 downward. This results in both of the fibre washers being forced down tight enough to form gas tight joints between the parts and prevent any leakage of gasoline from splash. The spring also anchors all the parts in position on the tank and also provides sufficient friction to the hub 17 to hold the handle 5 in its different adjusted positions. This friction is not sufficient however to interfere in any way with the free operation of the handle 5 or the arm or handle 25 shown in Figure 9. This is particularly desirable in connection with the devices shown in Figure 9 and which are operated from the instrument board of the machine. In devices of this character it is too expensive and cumbersome to try and operate devices at the rear of the machine with rods, levers or gears which would be necessary in the operation of such devices that required any considerable degree of force.

In order to employ the cheap and efficient so called "Boden" shaft comprising a coil of spring wire enclosing a loose longitudinally movable wire, it is necessary to provide devices that will operate with a minimum amount of friction and that require very little force. If the devices require any considerable force to operate them, the "Boden" shaft will not operate as the resistance at one end of the shaft or wire will cause the wire to simply expand the coil or tube enclosing it and there will be no movement of the wire at the end opposite to that at which the operative force is applied. As far as applicant knows no devices have yet been devised that are effective in controlling the reserve and at the same time work so freely that they can be worked from a distance with a device of the character of the "Boden" shaft. With taper valves and all other valves which must act as valves "in the line" the force required to operate them is considerable. The "Boden" shaft could not be used in such cases. It is the very peculiar construction of applicant's reserve control that permits the employment of loose fitting sleeves and other parts that a child can operate and still retains efficiency and accomplishes the object sought without any sticking and without any leaking of gasoline. It will be understood that this result is accomplished by locating the air vent 3^a in the gasoline tank and submerging the same with the main contents of the tank and that the fuel is fed through the opening 3^a as well as through the open end of the pipe and that this feed does not stop until the level of the gasoline descends below the level of the opening 3^a when air enters the pipe 3 through this opening and the feed of the gasoline stops. Should the opening 3^a be

only partly closed and only partly destroy the vacuum in the pipe 3, the feed would still continue as only a very slight vacuum in the pipe 3 would be necessary to raise the gasoline, the inch or two that would be necessary to take it past the opening 3^a when it would receive the full vacuum. Applicant has taken advantage of this construction and operation to provide a freely operating valve or sleeve which might very well be compared to a loose or partly open valve. This peculiar function of applicant's device is fully set forth in applicant's first hereinbefore mentioned patent.

In the modified form of applicant's invention shown in Figure 9 the handle 5 is replaced with an arm or handle 25, the other parts being the same with the exception that the attaching nipple 20 projects at a right angle to the position it occupies in Figure 2. This arm 25, as shown in Figure 12, is bifurcated at its end as at 34 to receive the apertured block 35 through which the pivot bolt 26 passes. The block 35 is formed with an apertured shank 27, see Figure 9, in which the end of the wire 28 is brazed or soldered. This wire 28 passes through a flexible tube 29 formed from a coil of spring wire. This tube 29 is secured in position at the tank end by being clamped to the fuel pipe 2 by a clamp member 32^a. The clamping portions 33 and 34 of this clamp are clamped to the pipe 2 and the tube 29 respectively by clamping screws 31 and 32 as best shown in Figure 8. This clamp brings the thrust and pull of the wire 28 in direct line with the pivot pin or bolt 26 when the lever 25 is in either of its set positions. As the lever 25 passes from one to the other of its positions the wire 28 bends to permit such action which is out of direct line, but as this wire is a spring wire the operation is smooth and even. This is an additional means of holding the lever set in its adjusted positions. The dash board end of the wire 28 is secured by soldering or otherwise in a shank 37 having an operating head 36. This shank is mounted in a tube 57 having an attaching plate 38 which is secured by bolts 39 to the instrument board 40 of the machine. The end of the coil 29 is clamped in the lower end of the tube 57. When the parts are in the position shown in Figure 9 the stem 37 is projecting from the dash board and is a constant reminder to the driver that the reserve supply is being used and that he should have the tank refilled. After the tank has been refilled this shank extending from the dash reminds the operator that he has not reset the device as he should. When the parts are in the position shown in Figure 9 the opening 3^a is closed and the reserve is being drawn on but when the knob 36 is depressed and the

shank 37 forced into the tube 57 the wire 28 is moved longitudinally in the tube 29 and the lever 25 is moved to the position shown in dotted lines in which the sleeve 4 opens the air vent 3^a. This is the main running position. After the main supply of the gasoline is exhausted the knob 36 is pulled out and the reserve is available. This reserve is good for about twenty five miles or more according to the mileage per gallon of the machine. After the device has been in use for a while and the operator becomes familiar with it, he is informed by the missing of his engine, when it is about to stop, by the main supply becoming exhausted, and by pulling out the knob 36 at once he is enabled to go ahead upon his reserve without the engine stopping.

As the knob 36 is so located on the instrument board that it is in plain sight every time the operator looks at the board it is sufficient reminder as to the adjustments of the parts to prevent the parts being accidentally left in the wrong adjustments.

In the modified form of my invention shown in Figure 10 the unbroken fuel feeding pipe 53 extends down into the tank just as in the first instance. The sliding sleeve 54 formed with a port 56 covers and uncovers a corresponding port in the pipe 53. This sleeve is provided with an extension 55 into which is screwed the lower end of a rod 50. This rod extends up through a passage 46 formed in an attaching nipple 49 having screw threads 47 for attaching it to the tank as in Figure 1. The rod 50 is bent into a handle 52 and is provided with a limiting collar 51. The upward movement of the handle 52 is limited by a pin 54^a on the pipe 53. This pipe is set in the nipple 49 which latter is formed with threads for the attachment of the pipe line. In this form raising and lowering the sleeve 54 brings the reserve or the main supply into connection with the feed pipe.

It will be seen from the foregoing that by this peculiar construction allowing for a very loose fitting valve, that I am enabled to use the telescoping sleeves and secure a very compact and very desirable construction which allows the application without change, of different size attaching nipples. If it were necessary to have the telescoping sleeves fit closely together, the construction would not be practical for use submerged in gasoline or other liquid of a corroding nature. The close fitting sleeves would soon become locked together by corrosion and could not be operated.

The peculiar mounting of the tank end of the tube 29 by attaching it to the gasoline feed tube secures a toggle action or operation of the arm 25. This arm is secured to the sleeve 4 which is free to rotate, while the tube 29 is secured to the feed pipe which

practically passes down inside of the sleeve. The turning of the sleeve would thus have a tendency to turn the tube 3 with it, but the very force that is turning the sleeve is anchored to and starting its thrust from the rigid connection of the tube 3 and thus tends to turn the tube in the opposite direction.

The question of easy operation in devices of the character herein described is a vital 10 one and marks the line between practical and impractical devices. About 14 feet of flexible tubing is necessary in the dash controlled device and should the valve operation at the rear require any considerable 15 force to operate it, the coils of the tube would simply expand without any operation taking place at the rear of the machine as before described.

To insert different sized nipples 6 the pin 20 11 is pulled out and the spring 8 removed. The handle or lever 25 may of course be operated at the rear of the machine if desired.

The rod 50 is held in its adjusted positions by friction between the rod and the nipple 49 through which it passes. An additional safeguard is the fact that when the rod 50 is in its lower position the reserve is 25 "Off" and should the rod jar to this position 30 at any time after being raised it will simply stop the engine again and the operator will have to reset it.

Having thus described my invention what I claim as new and desire to secure by Letters Patent is:

1. The combination with a fuel tank, of an unbroken freely rotatable, apertured fuel feeding pipe extending down into the tank and having an attaching nipple, a freely 40 rotatable apertured valve sleeve surrounding and supporting the pipe movably within the tank means to rotate the sleeve to open and close the aperture in the pipe to feed the main supply or the reserve supply, and 45 means for anchoring the valve sleeve to the top of the tank but leaving it free to be rotated at will without moving the inner feed pipe.

2. The combination with a fuel tank, of 50 an unbroken feed pipe extending down into the same and having an air vent at a certain distance from its lower open end, an apertured sleeve surrounding the exterior of the pipe means to rotate the sleeve to open

and close the air vent, an attaching nipple 55 and a spring for anchoring the parts in position.

3. The combination with a fuel tank, of an unbroken feed pipe extending down into the same and having an air vent at a certain 60 distance from its lower open end, an apertured sleeve surrounding the exterior of the pipe and movable to open and close the air vent, an attaching nipple surrounding the sleeve, an expanding spring also surrounding 65 the sleeve, means on the feed pipe engaged and means for operating the apertured sleeve by the spring for anchoring the pipe in position.

4. The combination with a fuel tank, of 70 an unbroken feed pipe extending down into the same and having an air vent at a certain distance from its lower open end, a sleeve surrounding the exterior of the pipe and movable to open and close the air vent, 75 a handle exterior of the tank for operating the sleeve, a spring forcing the sleeve and pipe downward, an attaching nipple surrounding the sleeve, and a gas tight packing interposed above the nipple and drawn into 80 position by the spring.

5. The combination with a fuel tank, of an unbroken feed pipe extending down into the same and having an air vent at a certain 85 distance from its lower open end, a sleeve surrounding the exterior of the pipe for opening and closing the air vent, means for limiting the movements of the sleeve, a spring for anchoring the sleeve and the pipe in position, an attaching nipple surrounding 90 the sleeve and means for operating the sleeve.

6. The combination with a fuel tank, of an unbroken feed pipe extending down into the same and having an air vent at a certain 95 distance from the bottom of the tank, a sleeve surrounding the exterior of the pipe for opening and closing the air vent and leaving the pipe unbroken except for the air vent, a handle exterior of the tank for 100 operating the sleeve, an attaching nipple surrounding the sleeve, and a detachable spring for holding the parts together so that different sized nipples may be substituted at will.

In testimony whereof I affix my signature.

WILLIAM H. MUZZY.
